UNITED STATES PATENT OFFICE

FRED H. KING, OF CANTON, OHIO

TRIPLE-CAM-DRIVE GASOLINE ENGINE

Application filed February 17, 1928. Serial No. 255,099.

This invention has particular relation to steam gas and petrol engines and which embodies among other characteristics a cam drive mechanism adapted to increase the power thereof.

Another object of the invention comprehends a multiple cam member operating from the drive or crank shaft and adapted for direct driving connection with the engine pistons whereby the employment of connecting rods and bearings therefor is obviated.

A further object of the invention contemplates means adapted to establish connection between pairs of pistons whereby both will operate simultaneously to occupy their respective alternate positions.

More specifically stated, the pistons are provided with roller members adapted for engagement with the faces of the cam to relieve friction and to effect aligning of the pistons within their respective cylinder bores.

With the above and other objects in view, the invention further consists of the following novel features and details of construction, to be hereinafter more fully described, illustrated in the accompanying drawings and pointed out in the appended claim.

In the drawings:—

Figure 1 is a sectional view taken through a two-cylinder engine illustrating the connection of the cam member therewith.

Figure 2 is a side elevation of the drive shaft and cam member mounted thereon.

Figure 3 is a sectional view taken on line 3—3 of Figure 1.

Figure 4 is a longitudinal sectional view taken through a pair of the pistons and illustrating the connection of the connecting means and roller members mounted thereon.

Figure 5 is an elevation of a modified form of the piston.

Figure 6 is an elevation of the cam member illustrating the manner by means of which the same may be effectively employed to operate four cylinders.

Referring to the drawings in detail, wherein like characters of reference denote corresponding parts, the reference character 10 indicates a housing or crank case, or which 50 may be termed a cam case preferably cylin-

drical in contour, the purpose of which will be presently apparent. Cylinders 11, carried upon the housing, are so disposed to register the bores thereof with the interior of the housing in diametrically opposed relation. A 55 drive shaft 12, mounted within the housing, is adapted to support a cam member 13 thereon and which may be keyed, splined or otherwise rigidly connected therewith.

As best illustrated in Figures 1 and 6 of the drawings, the cam member 13 is provided with triple faces best adapted for motors having two and four cylinders respectively. Obviously, the number of faces upon the cam member may be changed commensurate with the number of cylinders in the particular engine or motor. A straight in line motor may be provided by mounting more cams on a single shaft.

Pistons 14 are carried within the cylinders 11. Plate members 15, extended within the pistons 14 are adapted to lie flush against the adjacent sides of fins 16 within said pistons and which are held against displacement therein through the instrumentality of pins 17.

As best illustrated in Figure 4 of the drawings, the plate members 15 are provided in pairs and spaced apart to provide a race-way to permit rotation of roller members 18 carried upon the pins 17. The plate members 15, are in addition, provided with elongated slotted portions 19 which extend the length of the plates between the adjacent ends of each pair of pistons. Bosses or hub portions 20, outstanding from the sides of the cam member 13 adjacent the spline or key connection of the drive shaft therewith, are adapted to engage the sides of the elongated slotted portions 19 in the connecting plates 15.

As best illustrated in Figure 1 of the drawings, the cam member 15 has faces 21 rounded to prevent friction when engaging the roller members 18 and arcuate shaped or curved portions 22 between the faces wherein one of the roller members may be disposed when the adjacent piston exercises a power stroke whereas the opposed piston is shifted to occupy the initial stroke position. As illustrated in Figure 1 of the drawings, the pis-

tons depend, as indicated at 23, upon diametrically opposite sides thereof adjacent the connection of the pins 17 therewith to provide stronger mountings for the latter and to permit ingress of the cam faces 21 of the member 13 when engaging and releasing each of the rollers 18.

In Figure 5 of the drawings, I have illustrated a piston 24, which instead of being provided with depending portions, as in the instance of the pistons 14, have portions removed or slotted portions 25 within diametrically opposed sides thereof and which are adapted to accommodate and permit passage of the cam faces 21 of the member 15 precedent and subsequent to engagement with the roller members 18. Obviously, the latter piston construction is the cheaper, as any form of piston could be cut away to provide a slot of sufficient dimensions to receive the cam faces.

In the two cylinder triple cam drive engine illustrated in Figure 1 of my drawings, it will be readily noted that six power strokes will be delivered in one and one-third revolutions of the drive shaft 12. A two cylinder crank shaft engine would deliver only one power stroke in one revolution. My particular type of triple cam drive engine will obviate many of the parts generally employed in the old style crank case engine, principally the friction bearings, crank shaft, connecting rods and fly wheel and yet derive three times as much power per revolution in contradistinction to the crank shaft engine.

It is readily seen that other cam members may be constructed having more faces to operate a corresponding number of pistons commensurate with the stroke of the pistons and power to be derived or developed.

By reason of the fact that the present invention obviates the employment of many of the parts necessary in the make-up of the crank shaft engine, it is to be noted that less friction would occur and consequently the burden is lightened, whereby the usual sluggishness apparent in the operation of the crank shaft engines will not exist.

The manifolds, valve mechanisms and ignition systems for the triple cam drive engines may be connected with the cylinders 11, after the manner of the rotary engine; although the cylinders in this instance are stationary. The pistons being provided with compression rings.

The invention is susceptible of various changes in its form, proportions and minor details of construction, and the right is herein reserved to make such changes as properly fall within the scope of the appended claim.

Having described the invention, what is claimed is:—

A cam drive engine comprising a housing provided with a multiplicity of cylinders adapted for communication therewith and

located upon opposite sides thereof, a shaft mounted within the housing and disposed at right angles to the bores of the cylinders, a single cam common to all the cylinders mounted upon the shaft and having rounded cam faces and curved raceways therebetween, plate members arranged in spaced parallelism upon opposite sides of the cam between and adapted to establish direct driving connections for the pistons of the cylinders and having registering elongated slotted portions therein, said pistons having portions removed upon diametrically opposite sides of the inner periphery thereof, bosses carried upon opposite sides of the cam adjacent the shaft being extended within the slotted portions of the plate members, and roller members carried within each of the pistons and journaled between the plates for engagement with the rounded ends and curved raceways of the cam through the guideways formed by the portions removed in the pistons.

In testimony whereof I affix my signature.

FRED H. KING.
